US0D1044539S

(12) **United States Design Patent** (10) **Patent No.:** **US D1,044,539 S**
(45) **Date of Patent:** **** Oct. 1, 2024**

(54) **TRACKER**

(71) Applicant: **Shenzhen Huanke Enterprise Management Co., Ltd.**, Guangdong (CN)

(72) Inventor: **Qiujian Liu**, Guangdong (CN)

(73) Assignee: **Shenzhen Huanke Enterprise Management**, Shenzhen (CN)

(**) Term: **15 Years**

(21) Appl. No.: **29/899,303**

(22) Filed: **Aug. 7, 2023**

(30) **Foreign Application Priority Data**

Jul. 7, 2023 (CN) 202330426526.6

(51) **LOC (14) Cl.** **10-04**

(52) **U.S. Cl.**

USPC **D10/70**; D10/104.1; D10/121

(58) **Field of Classification Search**

USPC ..... D10/100, 70, 104.1, 80, 11, 9.2, 120, D10/121, 74, 106.1–106.9, D10/106.91–106.95; D14/440, 240, 242, D14/300, 383–385, 341; D3/218, 215; D11/43, 52, 79, 80, 81, 60, 221, 207; D24/186; D13/168; D30/199; D19/10 CPC .. (57) **CLAIM**

The ornamental design for a tracker, as shown and described.

DESCRIPTION

FIG. 1 is a first perspective view of a tracker showing my new design;

FIG. 2 is a second perspective view thereof;

FIG. 3 is a front view of FIG. 1;

FIG. 4 is a rear view of FIG. 1;

FIG. 5 is a left side view of FIG. 1;

FIG. 6 is a right side view of FIG. 1;

FIG. 7 is a top plan view of FIG. 1; and,

FIG. 8 is a bottom plan view of FIG. 1.

The broken lines in the drawings depict portions of the tracker that form no part of the claimed design.

1 Claim, 8 Drawing Sheets
